UNITED STATES PATENT OFFICE.

ROBERT E. CARMICHAEL, OF DAMON, TEXAS, ASSIGNOR OF ONE-HALF TO GEORGE HAMMAN, OF HOUSTON, TEXAS.

PIPE-WRENCH.

1,324,302.

Specification of Letters Patent.

Patented Dec. 9, 1919.

Application filed March 7, 1919. Serial No. 281,216.

To all whom it may concern:

Be it known that I, ROBERT E. CARMICHAEL, a citizen of the United States, residing at Damon, Texas, county of Brazoria, have 5 invented a certain new and useful Improvement in Pipe-Wrenches, of which the following is a full, clear, and exact description, such as will enable others skilled in the art to which it appertains to make and use the 10 same.

My invention relates to an improvement in pipe wrenches. It has special application to pipe wrenches used in well drilling and similar operations, but may be used in any 15 operations in which a pipe wrench of strong construction is required.

An object of my invention is to provide a pipe wrench which will be capable of operation in either direction as desired, and 20 which will be strong in construction and easily manipulated. Another object is to provide a pipe wrench which will not only be strong in construction but capable of rapid adjustment to different sizes of pipe 25 within moderate limits.

Referring to the drawings forming a part of this specification and wherein like parts are referred to by like characters of reference throughout the several views, Figure 1 30 is a side elevation of my improved device with the chain omitted; Figs. 2 and 3 are profile views of one of the jaws used in connection therewith; Fig. 4 is a view of the handle and the head thereon, to which the 35 attaching means is secured; Fig. 5 is a side elevation taken at right angles to the view shown in Fig. 1, showing the jaws in their forward position; Figs. 6 and 7 are views of one of the links used in the chain employed 40 in connection with my invention; Fig. 8 is a view similar to that shown in Fig. 5, showing the jaws and chain in gripping position.

The head of my improved wrench or tongs comprises a rectangular block 1, of irregular 45 formation, having a reduced handle 2 integral therewith. The forward end of the head is provided with a transverse groove or concave portion 3 which may be toothed, as shown at 4 or may be plain as shown in the 50 other figures. On each of the side faces of the head are provided dove-tailed recesses 4 of large dimensions, extending transversely thereof. These recesses are adapted to accommodate the enlarged inner end of 55 the clamping jaws 5 and a retaining means

therefor. These jaws have, at their inner ends, an inwardly extending mortised member 6 adapted to fit slidably within the dove-tailed recess 4 of the head. On each side of the mortised member 6 and integral therewith, are two downwardly extending flanges 7, which are formed to over-lap the side of the head 1 of the wrench, so as to prevent lateral movement of the jaws, while in position, relative to the head 1. The rearward 60 end of the mortised member 6 of each of the jaws, is provided with a flattened face 8 for contact with a retaining member 9, against which the face 8 is adapted to contact. The main body of both of the jaws comprises a 70 flattened plate 10 fitting slidably upon the lateral face 11 at the forward end of the tool head. Two forwardly extending gripping portions 12 are provided on the forward end of the said jaws. Between the two said 75 gripping members is a slot or recess 13 through which an attaching chain 14 is adapted to play. On the outer face of one of the jaws is an upwardly extending staple 15, to which one end of said chain may be attached. The jaw on the opposite side of 80 said tool is provided with a hook 16 over which the chain may catch.

The retaining member 9 at the rear end of the two jaws has a backwardly extending 85 mortised portion 16' fitting within the rear end of the dove-tailed recess 4 which is deeper at this end as shown at 4' in Fig. 4, in the head. A forward face of this retaining member is shaped to fit the rear end of 90 the sliding jaw and has a forward mortised point 28 to prevent removal upwardly. The member 9 has a forwardly projecting supporting portion 17 to prevent the movement outwardly from the dove-tailed slot 4 of the 95 said jaws. The retaining members 9, are secured in position by the mortised portion and by means of a transversely extending bolt 18 which passes through the two jaws and through the transverse opening 19 in 100 the head, and is held securely by a nut thereon. Between the rearward faces 8 of the jaws and the retaining member 9 is positioned a helical spring 20. This spring is fitted within a recess in the forward face of 105 the member 9 and when compressed, will be inclosed entirely within said recess, but the said spring is capable of extension so as to normally force the jaws 5 to the forward end of the dove-tailed slots 4 of the head. 110

The chain 14, one end of which is attached to the staple 15 on one of the jaws, and the opposite end of which is adapted to latch over the hook member 16 on the opposite jaw, is preferably made up of links such as are shown in Figs. 6 and 7. This form of chain, however, is only one of many ordinary forms of chain which might be used on my device. The links making up this chain have a forward hooked member 21, somewhat narrower than the full width of the link and adapted to fit within the adjacent connecting link and over the opposite end 22 of said adjacent link. An opening or slot 23 on the hooked end of the link, when turned upwardly at right angles to the adjacent link to which it is attached, will be adapted to pass over the end 22 of said link, through a notch or recess 24 at one side thereof. When the links are then extended, the same cannot be detached. This form of link is of common construction and does not constitute a part of my invention, but is illustrated as one of the preferred forms of link which may be used, because it is easily repaired when one link is broken. By simply taking out the broken link and placing a new link in place of the broken one by sliding the hooked end of one of the new links over the opposite end of the adjacent link and connecting the same in line with the rest of the chain, the tool is again ready for use.

At each side of the central portion of the link, I have shown a tooth 25 which is square in cross section and adapted to fit within a similar shaped groove or recess in the inner face of the said link, in such manner that one of the points 26 thereof will project outwardly from the face of the link so as to grip the pipe with which it comes in contact. This tooth may be made of hardened steel, and as will be noted, may be turned when dull so that another angle of the same will contact with the pipe and when no longer usable another tooth may be substituted therefor.

In the operation of my device the chain is loosened from the hook member 16 and the gripping members 12 of the jaws are placed upon the pipe 27 to be operated upon. The pipe then fits against the forward groove 3 in the head and the chain 14 is pulled tightly about the pipe and is caught over the hook 16 on the opposite jaw. This position of the jaws is illustrated in Fig. 5. Both of the jaws will be at the forward ends of the slots 4 and the chain will be gripped as tightly as possible over the hook 16. It will be obvious that some play will usually occur in the chain 14, due to the fact that there is bound to be some slack in the chain after it has been caught over the hook 16. The wrench may be turned either way on the pipe, and in Fig. 8 the handle is sup-

posed to be turned in a counter-clockwise direction about the pipe 27. The pipe will then roll slightly within the grooved end 3 of the head of the wrench coming in tight gripping contact with the left hand jaw, as shown in Fig. 8. This jaw will then be shoved, by the continued movement of the handle, backwardly against the action of the spring 20, into contact with the retaining member 9. The other jaw will remain in its forward position. The lateral rolling or sliding of the pipe 27 upon the head, together with the backward slipping of the jaw 5 with which it contacts, will serve to tighten or take up the slack in the chain 14 so that the teeth 26 thereon will obtain a tight gripping hold upon the pipe. Continued movement of the handle in the same direction will then serve to rotate the pipe itself. It is obvious that the pipe can be also turned in the opposite direction and that the same action in the reverse direction will take place between the jaws and the pipe.

When it is desired that the jaws slip on the pipe, when the handle is turned, in one direction and to grip the pipe when it is turned in the other direction, in order that the handle may be reciprocated to turn the pipe, as is sometime necessary, one gripping portion 12 of one of the jaws 5 may be made plain instead of toothed in an obvious manner so that the swing of the handle in that direction will not serve to grip the pipe sufficiently to rotate the same but when the handle is swung in the opposite direction so as to bring the pipe into contact with the toothed portion 12 of the opposite jaw the pipe will be gripped so as to cause it to be rotated.

Having thus described my invention, the objects and advantages of which will be clear without further description, what I claim as new and desire to protect by Letters Patent is:

1. In a pipe wrench, a head, jaws adapted for slidable movement on opposite faces thereof, said jaws having forwardly projecting gripping surfaces for contact with the pipe, and a chain connecting the two said jaws.

2. A pipe wrench comprising a head, dove-tailed recesses in opposite faces thereof, gripping jaws having mortised ends adapted to fit within said recesses, means adapted to hold said jaws slidably within said recesses and a chain connecting the said jaws.

3. In a pipe wrench, a head, a dove-tailed recess in opposite faces of said head, jaws adapted to slide within said recesses, detachable retaining members to hold said jaws in said recesses, toothed gripping portions on the forward ends of said jaws and means connected with said jaws to hold said jaws on the pipe.

4. In a pipe wrench, a head provided with recesses therein, jaws slideable in said recesses, a chain adapted to connect said jaws and the pipe to be operated upon, and means to secure said jaws against displacement from said head.

5. In a pipe wrench, a head provided with dove-tailed recesses in opposite faces thereof, jaws adapted to slide within said recesses, a chain adapted to connect said jaws, retaining members fitting within one end of said recesses and over-lapping said jaws, and means on said retaining members to hold said jaws toward the forward end of said recesses.

6. In a pipe wrench, a head, jaws thereon, means to retain said jaws slideably on said head, there being gripping portions on said jaws, outwardly extending attaching members on said jaws and a chain secured to said attaching members.

7. In a pipe wrench, a head, jaws slideable thereon, a retaining means to hold said jaws on said head, a chain detachably connecting

said jaws and resilient means coöperating with said retaining means and said jaws to press the jaws toward the forward end of said head.

8. In a pipe wrench, a head, gripping jaws, means to retain said jaws slideably on said head, resilient means to press said jaws toward the forward end of said head, and a chain connecting said jaws and adapted to coöperate with said jaws in the manner described.

9. In a pipe wrench, a head having recesses therein, jaws retained slideably and non-rotatably in said recesses, and means connecting said jaws and operating to hold said jaws on the work.

10. In a pipe wrench, a head, jaws retained slideably thereon, and means connecting said jaws and coöperating therewith to retain the jaws on the work and also acting to grip the work.

In testimony whereof, I hereunto affix my signature this the 4th day of March, 1919.

ROBERT E. CARMICHAEL.
